APPARATUS FOR MAKING PISTONS

George H. Blettner, Chicago, Ill., assignor to
 Renette Company, Chicago, Ill., a corporation
 of Illinois

Application March 2, 1935, Serial No. 8,987

5 Claims. (Cl. 22—149)

The present invention relates to an apparatus for making pistons and more particularly to a one piece piston, and so constructed and made as to enable its manufacture in quantity lots on 5 a production basis whereby the pistons may be sold at relatively low prices.

An object of the present invention is to provide an apparatus for molding a piston in horizontal position, which apparatus may be quickly 10 and readily operated and in which a one piece core is employed in the mold cavity, which core is adapted to be withdrawn from the casting by horizontal movement.

Another object of the present invention is to 15 provide a one piece core for use in the manufacture of internal combustion engine and other pistons which core has self-contained extensible and retractile members or studs or radial projections or extensions to form the spaces between the wrist pin bosses and piston head.

A further object of the present invention has to do with a novel apparatus for casting internal combustion engine pistons in multiples or in groups of two or more at a time, in which the 20 axes of the piston cavities are horizontal and the skirt portions extend away from each other, the apparatus being so constructed that metal is supplied to the larger voids of the piston cavities during cooling to compensate for crystallization 25 shrinkage.

Another and yet further object of the present invention is to provide an apparatus especially adapted to be rapidly operated for the manufacture of pistons on a production basis and so constructed with one piece cores that the cores are 30 always accurately positioned in the mold cavities to insure uniformity of all castings made.

The invention has for an additional object the provision of a novel one piece core structure for 35 use in casting pistons for internal combustion engines.

Generally speaking the invention contemplates a permanent mold structure of two complementary sections or parts which are moved 40 against or away from each other, in each of which sections is formed a plurality of complementary cavities for forming two pistons in horizontal positions with their heads in adjacent 45 relationship and the cavities opening toward the ends of the mold structure. Each section also is provided with recesses forming part of an ingate, risers, sprue, and an enlargement or expansion ball in the ingate disposed between the adjacent ends of the cavities for forming the 50

heads of the pistons to supply metal to the heavier sections of the pistons during crystallization shrinkage.

The invention further contemplates a one piece core which is shaped to form the inside contour 5 of the piston and which core is provided with two diametrically oppositely disposed movable studs.

The invention contemplates the formation of a multiple number of pistons at a time, thereby 10 expediting production and reducing labor costs.

The above other and further objects of the present invention will be apparent from the following description, accompanying drawings, and 15 appended claims.

The accompanying drawings illustrate one embodiment of an apparatus constructed in accordance with the principles of the present invention, arranged to cast two pistons at a time, and the views thereof are as follows:

Figure 1 is a side elevational view of one of the mold sections in casting position, with the cores in place, illustrating one manner of supporting the cores, and indicating, fragmentarily, means for moving the cores axially into and out 20 of casting position.

Figure 2 is an axial section through a piston constructed in accordance with the principles of the present invention, and showing the piston after it has been machined and in completed 25 form.

Figure 3 is a transverse sectional view taken substantially in the plane indicated by line III—III of Fig. 2.

Figure 4 is an elevational view of the novel core 35 of the present invention.

Figure 5 is an axial section through the core of Figure 4.

Figure 6 is an end view of the core of Figure 40 4, looking at the right hand end of the same.

Figure 7 is an elevational view of the extensible and retractile members or studs carried by the core for forming the recesses or spaces in the piston between the wrist pin bosses and the piston head, showing the members in full lines 45 in retracted or nested position, and in dotted lines in extended or casting position.

Figure 8 is an axial sectional view, with a mold section and the cores in elevation and showing, 50 in section, the cast pistons, the ingate, expansion ball, risers and the sprue, and illustrating the method of the present invention.

Figure 9 is a transverse vertical sectional view through the mold and a cast piston, and showing 55

core prints in place for forming the wrist pin holes in the bosses. This view is a sectional view with the core removed, for clearness.

Figure 10 is a rear elevational view of one of the extensible and retractable members or studs of the core.

The drawings will now be explained.

The illustrated form of permanent mold consists of two sections A and B which are adapted to be moved against or away from each other. The sections are shown as hingedly connected by means of legs 1 and 2 on the sections A and B respectively which legs in turn are secured by bolts 3 and 4 to flanges 5 and 6 of a hinge which comprises eyes 7 and 8 and receiving a pintle pin 9.

The particular manner of mounting the mold on a standard support has not been illustrated as this may be accomplished in any well known and desirable manner.

Each of the mold sections is provided with complementary recesses which, when the sections are together, form the mold cavities, the ingate and the risers.

25 The section A is provided with two horizontally disposed cylindrical cavities 10, which are axially spaced; two riser cavities 11, of relatively shallow depth; an ingate 12 fashioned with an enlargement or expansion ball 13 disposed between the piston cavities 10 and connected thereto by passages 14 which communicates with the cavities substantially in horizontal direction, including the cavity axes, when the mold is in casting position; the lower end of the ingate 12 communicates with axially extending cavity or sprue 15 which also supplies molten metal to the piston cavities from the bottoms of the same. The sprue cavity 15 is shallow as may be observed in Fig. 9.

40 Each mold section is, at its ends, provided with a semi-cylindrical seat 16 for receiving and encompassing the cores which are inserted endwise into the mold cavities by axial movement and removed therefrom by axial movement in the reverse direction.

45 Each of the mold sections is provided with an upstanding head or neck 17 to form a bullet mold entrance for the ingate, and which extends above the mold sections to provide a head of molten metal to compensate for crystallization shrinkage as the castings cool.

As the two cores are alike in every respect, the description of one will suffice for both.

A core is fashioned from a block of steel and 55 comprises an end flange 18, a section 19 of reduced diameter, next to which is another section 20 of slightly less diameter, with the balance 21, in the main, cylindrical. The flange 18 on the several sections are substantially cylindrical in 60 cross section, with the sections 20 and 21 slightly tapered in a direction away from the flange 18 so that the core may be readily removed from a casting. At two diametrically opposite areas, the section 21 is formed with depressions 22, the 65 inner ends that is, the ends near the flange 18, are substantially semi-circular with the margins thereof opening toward the other end of the core body with their sides slightly divergent outwardly from the semi-circular ends. A wall 23 70 is fashioned in each of the depressions lying inwardly of the surface of the section 21 adjacent the depressions and slightly inclined inwardly toward the inner end of the core, that is, the end opposite that on which the flange 18 is, which 75 walls 23 serve as abutments for the ends of core

prints inserted in the mold sections A and B for fashioning the holes in the wrist pin bosses of the piston.

Secured in the core are two members or studs 24 and 25 which are adapted to be movable radially inwardly and outwardly, with respect to the core axis for forming the spaces between the wrist pin bosses and the head of the piston when cast. The active ends of these members or studs 24 and 25 are shaped to form the recesses 26 in 10 the pistons, see Figs. 2 and 3.

Figure 10 is an inner elevational view of one of these members or studs which are constructed as counterparts, and reversed in endwise arrangement when assembled in the core. Each of 15 these studs is provided with an extension 27 in which is formed a slot 28, extending in a direction substantially parallel to the general direction of the walls 23 of the core.

The core body is bored at 29 and counterbored 20 at 30. An oscillatory rod 31 having a head 31a on it is inserted through the inner end of the core body prior to the application of the members or studs 24 and 25 to the core. The head 31a is cylindrical and carries two pins 32 and 33. The 25 pin 32 extends through the disc and has an end 32a projecting from the opposite face of the disc. The core body is provided with an arcuate recess 34 in which the projection 32a travels and which recess serves to limit the extent of rotative movement of the rod 31 in the core body.

The pins 32 and 33 enter the respective slots 28 in the two members 24 and 25, when assembled in the core body as shown in Figs. 5 and 7. The members or studs 24 and 25 are retracted by 35 oscillating the rod 31 in one direction, which would be clockwise as viewed in Fig. 7 and extended by oscillating the rod in the opposite direction to substantially the dotted line position of Figs. 5 and 7. The extent of separation 40 of the members or studs 24 and 25 is governed by the engagement of the extension 32a of the pin 32 in the arcuate recess 34 while the extent or movement in the opposite direction is limited by the two members coming together in retracted position, which is full line position of Figs. 5 and 7.

The members or studs 24 and 25 are retained against displacement with respect to the core by means of a cover plate 60 retained in position by means of screws 37 (Fig. 6).

In order to provide axially extending reinforcing ribs 38 on the interior of the skirt portion of the piston, the core is provided with axially extending grooves 39 which increase in depth toward the inner end of the core.

The outer end of the core is provided with a counterbore 40 which is threaded at 41 for a portion of its length to receive the threaded end of an operating rod 42, the rod is centrally bored to receive the rod 31.

A part of the apparatus includes two uprights 43 and 44 disposed in spaced relation to the ends of the mold and which uprights are provided with bearings 44 and 45 with which cooperate complementary bearing members 46 to receive the rods 42 of the two cores of the present apparatus.

In order to move the cores into and out of casting relationship, axially, with the molding cavities in the mold sections, the rods 42 are provided outwardly of the uprights 43 and 44 with blocks 47, each of which blocks carries trunnions 48 to which are pivotally connected swinging arms 49 adapted to move the rods 42.

The construction of the arms 49 is not fully shown but it is understood that these are piv-

totally arranged and actuated by any well known means.

To oscillate the rods 31 and the attached discs 31a, the extremities of the rods 31 are provided with handles 50 disposed outwardly of the uprights 43 and 44 and beyond the corresponding ends of the rods 42.

Each of the mold sections A and B is provided with a side opening 51 for receiving a core print 52 for the formation, in the finished piston, of the holes 53 for the wrist pin.

The meeting faces of the mold sections A and B are machined so as to afford a tight fit between these parts when the same are connected together in casting relation to prevent the escape of any molten metal through the joints between them.

The operation of the apparatus is as follows:

When it is desired to cast pistons utilizing the apparatus of the present invention, with the mold sections A and B together, the cores C and D are moved toward each other horizontally, by operation of the levers 49. This movement positions the cores C and D in proper relationship, within the mold cavities when the mold sections A and B are closed and so that the ends of the mold sections tightly fit about the sections 19 of the cores and the cores are then properly positioned within the mold cavities. The handles 50 are then actuated to oscillate the rods 31 in a direction to project or extend the members or studs 24 and 25, to dotted line position of Figs. 5 and 7. The core pins 52 having been previously inserted in the mold sections A and B, or if not previously inserted, may now be inserted and moved against the walls 24 of the cores. The parts are now in position for pouring the molten metal.

The metal is poured into the head 17 whereupon it passes downwardly through the ingate 12, through the sprue portion 15 of the gate and then upwardly within the mold cavities and eventually forming risers in the riser spaces 11. Sufficient molten metal is supplied to the mold to fill the ingate approximately to the upper extremity of the head 17, this, therefore, assures a sufficient head of molten metal in the ingate and the expansion ball to supply additional metal during cooling of the castings to compensate for the usual shrinkage. The provision of the enlargement or expansion ball 13 adjacent the heads of the pistons assures at all times a supply of metal to the head portions of the pistons, and other heavier sections, so as to assure that the heads are properly formed, and, due to the supply of metal during cooling, formation of cracks is prevented. The exterior of the pistons is fashioned by the mold cavities in the mold sections A and B, while the cores C and D form the interiors of these pistons. The extensions of the members or studs 24 and 25 provide spaces or recesses between the wrist pin bosses and the piston heads. The formation of the cores C and D is such, that axially extending reinforcing ribs 54 are cast in the pistons and also the wrist pin bosses 55. The ends of the skirt portions of the pistons are formed by the junction or shoulder between the portions 19 and 20 of the cores.

When the casting operation has been completed, the handles 50 are operated in counter direction to withdraw or retract the members or studs 24 or 25 within the cores C and D, and the rods 42 are then moved outwardly by actuation of the levers 49, to withdraw the cores from the pistons, then the mold sections A and B are

separated. When the mold sections A and B have been separated, the finished product consisting of the two pistons and such portions of metal as may lie within the portion 15 of the gate, and the riser spaces 11, as well as in the ingate 12, enlargement 13, and branches 14 is then removed from the mold, and when sufficiently cooled, the pistons are separated from the scrap by sawing.

The piston blanks formed by the apparatus of the present invention are then subjected to suitable machine operations to form the piston ring grooves 56, three of which are shown and also to machine the inner periphery of the skirt as at 57. The holes 53 in the wrist pin bosses 55 may be machined, if necessary. The piston is then processed to provide slots 58 affording communication between the lowermost piston ring groove and the interior of the piston for oil interchange in use. The outer portions of the piston are then ground to size and finish and the skirt is sawed to provide a split 59, which extends from one of the slots 58 to the margin of the skirt portion.

With an apparatus of the present invention as herein illustrated, it is possible to cast two pistons at a time for every pouring of metal, which pistons, because of their formation in permanent molds and with permanent cores, are uniformly cast in every respect, so that but little machining is necessary to be done to finish them.

The cores are provided with noses 60 which form the ribs 61 as integral parts of the undersides of the heads of the pistons, also as integral parts of the axially extending ribs 62 connecting the ribs 61 with the wrist pin bosses 55.

The nose of a core is fashioned by an endplate 60, shaped in elevation, as shown in Fig. 4 and retained in place by screw 37.

A piston made in accordance with the present invention is suitably reinforced and smoothly finished and in dimensions is substantially that of the finished piston.

The present invention lends itself to rapid production of uniform pistons so that the labor incidental to the molding operation is reduced to a minimum. The utilization of the permanent cores of the present invention is such that no time is lost in setting the cores for the casting operations, so that the casting operations may be expedited for quantity production.

The provision of the enlargement or expansion ball 13, in the ingate, together with the risers and the sprue portion 15 of the gate is such that every casting formed is full, free from cracks and blowholes, and of uniform texture throughout.

If desired, the members or studs 24 and 25 could be eliminated which would result in thicker sections between the wrist pin bosses and the piston heads. The provision of the enlargement or feeder 13 in the ingate assures supply of metal to such thicker sections during shrinkage.

In removing the cores from the finished castings, the core prints 52 are withdrawn first and then the cores.

The invention has been described herein more or less precisely as to details, yet it is to be understood that the invention is not to be limited thereby, as changes may be made in the arrangement and proportion of parts and equivalents may be substituted without departing from the spirit and scope of the invention.

The invention is claimed as follows:

1. A casting apparatus for molding pistons in-

cluding a pair of metallic mold parts hinged together for movement toward and away from each other, each of said parts having two horizontal complementary cylindrical axially spaced mold cavities opening through the ends of said parts and with the head ends in opposed relation and an ingate leading between the head ends of said cavities, formed therein; metallic cylindrical cores supported to lie horizontally within the mold cavities when said mold parts are together in casting relation; said cores being axially movable so as to be withdrawn from the castings after the molding of the castings; said mold parts adapted to seat about said cores in sealing relation to cooperate therewith to form the remote ends of the mold cavities; said mold parts having openings to receive core prints for the wrist pin openings in the casting; said cores having diametrically opposite substantially flat portions against which the inner ends of said core prints abut; said cores having radially extensible and retractible studs for forming lateral recesses in the castings; and means entering said cores and operable while the mold parts are together for actuating said core studs into and out of molding position.

2. An apparatus for group casting of pistons comprising a mold formed with a common runner arranged to supply metal to a plurality of piston casting cavities, said mold being formed with a plurality of piston casting cavities arranged with the axes of the cavities horizontal and with the head ends of said cavities in proximity to said common runner and the skirt ends 35 extending away from the common runner, means for supporting cores in the skirt ends of said cavities to close said ends and form the interiors of the pistons, and a plurality of connections between said common runner and each of said cavities to supply molten metal to the larger voids of the cavities to compensate for shrinkage of the castings while cooling.

3. An apparatus for group casting of pistons comprising a mold formed with a common runner arranged to supply metal to a plurality of piston casting cavities, said mold having formed in it a plurality of piston casting cavities arranged with the axes of the cavities horizontal and with the head forming ends of said cavities 50 in proximity to said common runner and the

skirt ends extending away from the common runner, cores supported in the skirt ends of said cavities to close said ends and form the interiors of the pistons, and said mold having a plurality of connections between said common runner and each of said cavities so arranged that the center lines of certain of said connections lie in horizontal planes which includes the horizontal axes of the cavities when the mold is in casting position.

4. In an apparatus for the group casting of pistons which comprises a mold formed with a common runner arranged to supply metal to a plurality of piston casting cavities, said runner being in vertical position when casting, said mold 15 being formed with a plurality of piston casting cavities arranged with the axes of the cavities horizontal and with the head ends of said cavities in proximity to said common runner and with the skirt ends of the cavities extending 20 away from the common runner, cores supported in the skirt ends of said cavities to form the interiors of the pistons and close said ends, and said mold being formed with connections between said common runner and said cavities, certain 25 of said connections being so arranged that the centers thereof lie in vertical planes including the cavity axes when the mold is in casting position.

5. An apparatus for the group casting of 30 pistons which includes a mold formed with a common runner which extends vertically when in casting position and downwardly between a plurality of piston cavities, said mold being formed with a plurality of piston cavities in it 35 arranged with the head forming ends of said cavities towards the common runner and their axes at right angles to the longitudinal axis of the runner, means for supporting cores in the other ends of said cavities to form the interiors 40 of the pistons and close the ends of the cavities, and said mold having formed in it a plurality of substantially horizontal connections between said runner and each of said cavities, certain of said connections communicating with said cavities at substantially mid-height of said cavities when in casting position to supply metal to the larger voids in said cavities to compensate for shrinkage of the castings while cooling.

GEORGE H. BLETTNER.
